CLAIM

The ornamental design for a checkout counter, as shown and described.

DESCRIPTION

FIG. 1 is a perspective view of a checkout counter showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The diagonal shade lines indicate transparency.

The broken lines illustrate portions of the article which form no part of the claimed design.

1 Claim, 6 Drawing Sheets
